CABINET PULL OR THE LIKE

Vytant P. Aleks, Rockford, Ill., assignor to National Lock Co., Rockford, Ill., a corporation of Delaware

Filed Dec. 9, 1959, Ser. No. 58,614

Term of patent 14 years

(Cl. D10—8)

Fig. 1.

Fig. 2.

Fig. 3.

Fig. 4.

Fig. 1 is a top plan view of a cabinet pull or the like embodying my new design;

Fig. 2 is a front elevation thereof;

Fig. 3 is a rear elevation thereof; and

Fig. 4 is an end elevation thereof.

I claim:

The ornamental design for a cabinet pull or the like,
substantially as shown.
